LAMP

Edwin H. Land, Boston, Mass., assignor to
Polaroid Corporation, Dover, Del., a corpora-
tion of Delaware

Application August 1, 1940, Serial No. 349,157

1 Claim. (CL 88—65)

This invention relates to lamps, and more particularly to lamps adapted to emit polarized light.

It is a particular object of this invention to provide a lamp adapted to illuminate a flat surface such, for example, as a book or magazine, positioned between said lamp and the user thereof.

Another object is to provide such a lamp which is adapted to emit only light vibrating in the plane of incidence on the surface to be illuminated, and from which the light vibrating parallel to said surface has been eliminated.

A further object of the invention is to provide such a lamp wherein the polarizing element or elements are so positioned that at least a part of the undesired component of the light is eliminated by reflection from the surfaces of said polarizing element or elements.

Other objects of the invention will in part appear and in part be pointed out in the course of the following description of one embodiment of the invention, which is given as a non-limiting example in connection with the accompanying drawing, which is a side elevation, partly broken away, of a lamp embodying a form of the invention.

Said lamp comprises an incandescent bulb or other suitable source of light 5, mounted in a column member 6 provided with a base 8 of any suitable shape. Shade or shell member 10 is mounted on column 6 in any desired manner, and a reflecting element 12 is preferably provided positioned to direct light incident thereon out of the open portion 14 of said shell. The inside of said shell will also preferably be lined with suitable light-reflecting material.

In accordance with the practice of the invention, an element 15 which is adapted to polarize transmitted light is positioned in open portion 14 to polarize the light passing therethrough from bulb 5 and reflector 12. Said polarizing element is preferably sheet-like in form and may advantageously comprise dichroic, plastic materials such as the polarizing materials made and sold under the trade name "Polaroid." Polarizer 15 may be mounted in any convenient way such as by means of a series of projections 16 on the inside of shell 10 and screws or rivets 18 as shown.

The lamp of the present invention is intended particularly for use in illuminating a relatively flat surface such, for example, as a page of a book or magazine, positioned between the lamp and the user thereof. Such a flat surface is indicated at 20. The lamp of the invention is de-

signed to emit only light vibrating in the plane of incidence of said light upon the surface to be illuminated, that is to say, light vibrating parallel to the plane of the paper in the drawing. The component of the light vibrating parallel to the surface to be illuminated, which is the glare-producing component, is eliminated by means of the polarizing element 15.

In accordance with the practice of the invention, polarizing element 15 is so positioned in the lamp that at least a portion of the undesired component of the light from bulb 5 and reflector 12 is eliminated by reflection at the surfaces of said polarizing element. In a lamp used in the manner shown in the drawing, this will be accomplished by positioning said polarizing element with its surfaces substantially parallel to the surface to be illuminated. It will be seen that this condition will commonly be fulfilled by positioning element 15 with its surfaces substantially parallel to the bottom of base element 8.

Dotted line 22 indicates the course of a ray of light polarized by the lamp of the invention. Said ray is first reflected from reflector 12 and is then incident on the upper surface of polarizer 15, at which surface a portion of the horizontally vibrating component is reflected, as indicated at 24. Since it is the purpose of the lamp to eliminate this horizontally vibrating component and to facilitate transmission of the component vibrating at right angles thereto, this loss by reflection aids the purpose of the lamp. Ray 22 then continues through polarizer 15 and in the course of its passage therethrough, the remainder of the horizontally vibrating component is absorbed by the dichroic material of the polarizer. The remaining component 25, which includes only light vibrating parallel to its plane of incidence on element 15, continues on to illuminate surface 20. It will be noted that the intensity of ray 24 depends upon the angle at which ray 22 is incident on polarizer 15, and that for maximum efficiency the elements of the lamp should be so arranged that as much of the light as possible should strike the upper surface of the polarizer at angles approaching the polarizing angle of incidence.

It will be seen that the operation of the above described lamp is substantially the same whether or not element 15 comprises dichroic material. However, if it does comprise dichroic material, it should be noted that said element should be so positioned in the lamp that its transmission axis will be parallel to the plane of incidence thereon of ray 22. That is to say, said material

should be positioned to transmit only that component of the light from bulb 5 which is vibrating parallel to the plane of the paper in the drawing and to absorb that component of said light which is vibrating parallel to its surface, that is, perpendicular to the plane of the paper in the drawing.

It should be pointed out that the lamp of this invention is capable of other uses in addition to that illustrated in the drawing. For example, it may be used to excellent advantage to illuminate such objects as paintings hanging as on a wall. In such case, said lamp will preferably be positioned with polarizing element 15 perpendicular to the horizontal, but the surfaces of element 15 will still be parallel to the surface to be illuminated. Other such uses will doubtless be apparent to one skilled in the art and are to be construed as being within the scope of the invention.

Since certain changes may be made in the above construction and different embodiments of the invention could be made without departing from the scope of the invention, it is intended that all matter contained in the above description shall be interpreted as illustrative and not in a limiting sense.

It is also to be understood that the following

claim is intended to cover all of the generic and specific features of the invention herein described, and all statements of the scope of the invention which, as a matter of language, might be said to fall therebetween.

Having described my invention, what I claim as new and useful and desire to secure by Letters Patent is:

A lamp comprising, in combination, a base element having a substantially flat bottom surface, a reflector-shield, a column element connecting said shield element with said base element, said shield element extending laterally beyond said column element, a source of light positioned within said shield substantially in line with said column element, a substantially sheet-like element of dichroic light-polarizing material mounted within said laterally extending portion of said shield with the surfaces thereof substantially parallel to said flat surface of said base element, and means for directing the light emanating from said source upon said polarizing element at relatively large angles of incidence, said polarizing element being arranged with the transmission axis thereof substantially parallel to the plane of incidence thereon of said light.

EDWIN H. LAND.
